CLAIM

The ornamental design for a portable caddy for drinks, as shown and described.

DESCRIPTION

FIG. 1 is a front perspective view of a portable caddy for drinks, showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The trademark material “The Drink Caddy” on the top of the portable caddy for drinks is owned by the inventor and is not a registered trademark.

The broken lines in the figures illustrate the portions of the portable caddy for drinks that form no part of the claimed design.
